UNITED STATES PATENT OFFICE

GEORGE H. LACKNER, OF CINCINNATI, OHIO

DESIGN FOR A SIGN

Application filed December 29, 1930. Serial No. 38,148. Term of patent 7 years.

To all whom it may concern:

Be it known that I, GEORGE H. LACKNER, a citizen of the United States, residing at Cincinnati, in the county of Hamilton and State of Ohio, have invented a new, original, and ornamental Design for a Sign, of which the following is a specification, reference being had to the accompanying drawing, forming part thereof.

In the drawing the view is a front elevation of the sign.

The sign is of no appreciable third dimension, being substantially of the usual panel depth. The obverse side of the sign is also ornamented in the manner disclosed.

I claim:

The ornamental design for a sign, as shown and described.

GEORGE H. LACKNER.
